UNITED STATES PATENT OFFICE

149,224

DESIGN FOR AN EMBROIDERED TRIMMING
OR SIMILAR ARTICLE

Arno E. Riedel, North Bergen, N. J., assignor to Ellen Lace & Embroidery Co., New York, N. Y., a firm

Application April 26, 1947, Serial No. 138,629

Term of patent 3½ years

(Cl. D92—1)

To all whom it may concern:

Be it known that I, Arno E. Riedel, a citizen of the United States of America, residing at North Bergen, New Jersey, have invented a new, original, and ornamental, Design for an Embroidered Trimming or Similar Article, of which the following is a specification, reference being had to the accompanying drawing, forming a part thereof.

The figure is a plan view of an embroidered trimming showing my new design.

I claim:

The ornamental design for an embroidered trimming or similar article, as shown.

ARNO E. RIEDEL.
